UNITED STATES PATENT OFFICE.

CLARENCE H. KEELEY, OF VAN NUYS, CALIFORNIA.

CUCKOO HORN.

Application filed March 28, 1929. Serial No. 350,587.

This invention relates to an improved structure for horns, and more especially to the provision of a horn, for use on automobiles, or like vehicles, but which may be used for purposes other than a vehicle signal.

The primary object of the invention is to provide a horn of the character described, wherein the sound emitted therefrom will 10 closely resemble the cry of a cuckoo.

A further object of the invention is to provide a horn of this type, which may be quickly and easily assembled, and of a structure of suitable size, as to permit it being 15 placed in an automobile so as to be conveniently operated by the driver of the vehicle, which will be comparatively simple in structure, be sold at a nominal cost, strong, durable and otherwise well adapted for the 20 purpose intended.

A more clear knowledge of my invention will become apparent during a study of the following description taken in connection with the accompanying drawings, 25 wherein:

Figure 1 is a top plan view of my invention.

Figure 2 is a side elevation of the same.

Figure 3 is a longitudinal sectional view 30 thereof.

Figure 4 is a top plan view of the whistle structure with the cover removed.

Figure 5 is a top plan view of the same with the cover applied thereto, and

Figure 6 is a perspective view of the bracket structure.

With reference more in detail to the drawings it will be seen that my improved invention comprises a stationary member 1, 40 which stationary member 1 is an elongated rectangular shaped block of wood or suitable material, and is of sufficient thickness, so as to provide on its upper surface an intermediately disposed raised portion 5 from 45 which intermediate portion 5 the top surface of the block gradually slopes toward the opposite ends of the block as at 2 and 3, respectively.

Hingedly connected to the raised portion 5 50 of the stationary member 1 is a relatively thick, substantially rectangular shaped block 4 as at 5'. Formed in the block 4 is a pair of longitudinally extending slots 6 and 7, disposed in spaced parallelism, and the opposite ends of the slots 6 and 7 being dis-

posed, or terminating in spaced relation to the respective opposite ends of the block 4. The block 4 is further provided with a pair of circular cells 8 and 9, formed in the block intermediate one end of the respective slots 6 and the adjacent end of the block. Each of the cells 8 and 9 is provided with a small circular opening 11—11 for a purpose to be hereinafter more fully set forth. A covering 12 formed of a relatively flat substantially rectangular shaped piece of wood or similar material is disposed over the upper face of the block 4, and the covering 12 is provided with a pair of openings 13 and 14, which openings are disposed over the respective slots 6 and 7 at that end of the respective slots nearest to the cells 8 and 9.

It is to be noted that the top portion of the covering 12 adjacent each of the openings 13 and 14 is provided with an elongated slot 15 and 16, respectively, the bottom of which slots incline downwardly as at 15' and 16', respectively, terminating at the respective openings 13 and 14. It is also to be noted that when the covering 12 is disposed over the block 4 as shown to advantage in Figure 3, that the under surface of the block which extends over the cells is cut away as at 17 and again as at 18 to provide a communicating passage between the respective cells and the adjacent opening 13 or 14. Extending around the sides and ends of the stationary member 1 and the block 4 is an elongated piece of fabric 19, which fabric is of a flexible nature, the upper and lower edges of the fabric 19 being secured to the member 1 and the block 4, respectively, as best illustrated in Figure 3. If desired, a narrow flexible strip 20 is secured to the member 1 and the block 4 exteriorly of the fabric 19 as at 21—21 and as clearly illustrated in Figure 2. It is apparent that the fabric 19 extending about the members 1 and 4 as illustrated, provide an air space between the members so that when the block 4 is rocked in either direction on the member 1 the air within the said space is discharged from the block 4 following the line of direction indicated by the arrows.

One end of the block 4 is held in spaced 105 relation from the adjacent end of the stationary member 1 by means of a spring 22, one end of which spring is connected to the opposite end of the block 4 as at 23 and the other end of the spring being connected 110

to the adjacent end of the member 1 as at 24. Thus it will be seen that when pressure is applied to the opposite end of the block 4 for rocking the block upon the stationary member 1 the air in the air spaces between the member 1 and the block 4 will be discharged therefrom, since it is obvious that the air will be forced outwardly through the openings 11-11 of the cells 8 and 9 respectively, and through the cells and communicating passage between the cells and the openings 13 and 14 respectively, during the rocking movement of the block 4 upon the member 1. And it is obvious that in having the upper surface of the covering 14 slope as at 15' and 16' respectively, inclining toward the respective openings 13 and 14 a whistling sound is produced which is similar to the cry of a cuckoo.

20 In order to rigidly mount the horn conveniently within an automobile or other vehicle, or wherever else it may be desired, there is provided a bracket 25 having at one end a pair of spaced openings 26-26 for 25 attaching the same to the stationary member 1 of the horn by means of screws or other upwardly extending projections such as illustrated at 27 in Figure 2. Intermediate its ends the bracket is bent as at 28 to 30 terminate in a projection 29, the extreme end of the projection 29 being bent upon itself as at 30 for attaching the bracket to any suitable supporting structure.

If desired a strand of wire or any flexible material designated by the numeral 35 31 may have one end attached to the block 4 as at 32 so that by pull being applied to the strand 31 the block 4 may be rocked on the stationary member for operating the 40 horn.

From the foregoing it will be seen that I have provided an improved horn for use on automobiles or other like vehicles, or anywhere where it is desired to have a sounding device.

Thus it may be seen that the device is capable of use either as a signalling means or in connection with anything where one would want to produce such a sound as will resemble a cuckoo.

While I have herein described the member 1 as being stationary, and the block 4 as movable thereon, it is obvious that if desirable the block 4 may be stationary and the 55 member 1 actuated for sounding the horn.

Having thus described the invention, what I claim as new and desire to secure by Letters Patent is:

1. In a horn of the class described, a stationary member, a second member rockably mounted thereon, said second member comprising a rectangular shaped block having a slot formed therein, and a cell formed in the block adjacent one end of said slot, 60 65 an opening formed in the bottom of the

cell, an elongated fabric disposed about the sides and ends of the members, the upper and lower edges of the fabric being secured to the respective members, and a substantially flat covering for the second member, having an opening therein disposed over the slot at one end of the slot and communicating with the cell.

2. In a cuckoo horn, a stationary member, 75 a second member rockably mounted thereon, said second member comprising a rectangular shaped block having a pair of longitudinally extending spaced slots formed therein, the opposite ends of the respective slots terminating in spaced relation from the opposite ends of the block, a cell formed in the block adjacent the said opposite ends of the respective slots, an opening formed in the bottom of each of said cells, and a substantially flat rectangular shaped member disposed on the upper face of the block and having openings formed therein, each of said openings being disposed over the slot at one end of the slot and adjacent the respective cell, and the 90 inner face of said last mentioned member having that portion disposed over said cell cut away to provide a communicating passage between the cell and the opening in the member, and a flexible fabric extending 95 completely about the stationary member and said block, the upper and lower edges of the fabric being secured to the member and block respectively.

3. In a cockoo horn, a stationary member, 100 a second member rockably mounted thereon, said second member comprising a rectangular shaped block having a pair of longitudinally extending spaced slots formed therein, the opposite ends of the respective slots terminating in spaced relation from the opposite ends of the block, cells formed in the block adjacent the said opposite ends of the respective slots, an opening formed in the bottom of each of 105 said cells, and a substantially flat rectangular shaped member disposed on the upper face of the block and having openings formed therein, each of said openings being disposed over a slot at one end of the slot 110 and adjacent a cell, and the inner face of said last mentioned member having portions disposed over said cells cut away to provide communicating passages between the cells and said openings in the member, a 115 flexible fabric extending completely about the stationary member and said block, the upper and lower edges of the fabric being secured to the member and block respectively, and spring means for normally holding 120 one end of said block spaced from the adjacent end of said stationary member.

4. In a device of the class described, a stationary member, a rectangular shaped block rockably mounted on said member, a 125 130

pair of slots formed in said block, said slots being disposed in spaced parallelism, cells formed in the block adjacent opposite ends of said slots, a substantially flat member disposed over the upper face of said block, and having openings formed therein disposed over said slots and connected with said cells, means for providing an air space between said stationary member and said block, and a resilient connection between one end of the block and adjacent end of the stationary member.

5. In a device of the class described, a stationary member, a rectangular shaped block flexibly mounted on said member, flexible connecting means between one end of said block and the adjacent end of said stationary member, a relatively wide fabric extending around said stationary member 10 and said block to provide an air space between said member and said block, a pair of spaced parallel slots formed in the block, cells formed in the block adjacent the opposite ends of said slots, an opening formed 15 in each of said cells to permit the entrance of the air to the cells from said air space when pressure is applied to the opposite ends of the block for rocking the same, a covering for the slots and cells, and openings formed in the covering communicating 20 with the slots and cells.

6. A horn comprising two elements one of which is movable relatively to the other, and one of which has within it sound producing 25 means, and bellows means complementary to said elements and having its interior con-

nected with said sound producing means whereby compression of the bellows will be attended by the production of sound.

7. A horn comprising two elements one 40 of which is rockable relatively to the other, bellows means complementary to the end portions of said elements, and forming therewith bellows arranged to be compressed alternately, and two sound producing 45 means appurtenant to one of said elements and each in communication with the interior of one of said bellows, whereby said sound producing means will be actuated alternately incident to rocking of the 50 rockable elements.

8. A horn comprising two elements one of which is rockable relatively to the other, bellows means complementary to the end portions of said elements, and forming 55 therewith bellows arranged to be compressed alternately, and two sound producing means formed in the rockable elements and each in communication with the interior of one of said bellows and each having its induction opening at the upper side of the rockable elements.

9. A horn, means for supplying a blast of air, and an element at one side of said means and having a cell in communication therewith and a chamber spaced from said cell and also having a sound emission opening in communication with said chamber and connected through a passage with said cell.

In testimony whereof I affix my signature,

CLARENCE H. KEELEY.
